HANDLE GRIP FOR A SNOW SHOVEL OR SIMILAR ARTICLE

Walter R. Hart, Columbus, Ohio, assignor to The Union
Fork and Hoe Company, Columbus, Ohio

Filed Feb. 24, 1970, Ser. No. 21,581

Term of patent 14 years

Int. Cl. D8—01

U.S. Cl. D8—1

FIG. 1

FIG. 3

FIG. 1 is a top plan view of a handle grip for a snow shovel or similar article showing my new design;

FIG. 2 is a side elevational view thereof; and

FIG. 3 is an end elevational view looking toward the forward end of the handle grip.

I claim:

The ornamental design for a handle grip for a snow shovel or similar article, substantially as shown.
